UNITED STATES PATENT OFFICE.

AUGUSTUS E. SCHLIEDEE, OF DETROIT, MICHIGAN, ASSIGNEE TO SCHLIEDEER MANUFACTURING CO., OF DETROIT, MICHIGAN, A CORPORATION OF MICHIGAN.

MACHINE FOR TRIMMING VALVES.

1,346,259.

Specification of Letters Patent.

Patented July 13, 1920.

Application filed March 23, 1916. Serial No. 86,223.

To all whom it may concern:

Be it known that I, AUGUSTUS E. SCHLIEDEE, a citizen of the United States, residing at Detroit, in the county of Wayne 5 and State of Michigan, have invented certain new and useful Improvements in Machines for Trimming Valves, of which the following is a specification.

My invention relates to improvements in 10 machines for trimming valves, and more particularly for trimming the heads of puppet valves, such for example as are used as inlet and exhaust valves of explosive engines.

One of the objects of my invention is the 15 equipment of improved means to a screw machine, lathe, or other suitable metal working machine, for simultaneously trimming a plurality of faces or parts of a valve head 20 at a single operation.

A further object is to provide means for this purpose which can be quickly and conveniently adjusted for trimming the heads or disks of puppet valves of various sizes.

A still further object is to provide a machine in which valve heads or other objects, cast or otherwise formed to slightly larger size than they are to have when finished, will be trimmed in a more economical, 30 speedier and more expeditious manner than has heretofore been possible.

With these and other objects in view my invention consists in the novel features of construction; in the arrangement and combination of devices; and in the peculiar construction, arrangement and combination of parts and elements to be hereinafter described and more particularly pointed out in the subjoined claim.

Figure 1 is a side elevation of a screw machine equipped with my invention.

Fig. 2 is a plan view of the same with one end thereof broken away.

Fig. 3 is an enlarged cross section taken 45 on line 3-3, Fig. 1.

Fig. 4 is a vertical longitudinal section through the head stock of the machine and through the adjusting tool carrier adjacent thereto in which the cutting or trimming 50 tools acting against the inner or under side and the outer or upper side are carried.

Fig. 5 is a plan view of the several cutting tools, the work holding chuck, and the valve retained within said chuck.

Fig. 6 is a side elevation of one end of the

transversely-disposed tool carrier showing one of the tools of said carrier cutting against the head of the valve.

Reference now being had to the drawings in detail, similar numerals refer to similar 60 parts in the several figures.

The reference numeral 9 designates the frame of a metal working machine which, as illustrated in this instance, is a screw machine, but may be any other form of metal 65 working machine provided with suitable means for positioning the valve or other work-piece, and which is capable of having applied thereto the tool carriers movable toward and from the head of the valve or toward and from any other work-piece in a manner to be hereinafter described.

The frame 9 of the machine supports the bed or shears 10 which has a head stock 11 at one end provided with inner and outer 75 bearings 12, 13, respectively.

A hollow spindle 14 is journaled in the bearings 12, 13, to which the shell or casing of the work-gripping or holding chuck 15 is secured. Suitably fastened to the hollow 80 spindle 14 between the bearings 12, 13 is a cone pulley 16 having a driving belt 17 applied thereto to cause rotation of said spindle.

Slidably attached to the spindle 14 near 85 its outer end is a clutch ring 18, and fastened to said spindle adjacent said clutch ring is a collar 19 in which clutch levers 20 are pivotally secured; each clutch lever having a long arm 21 and a short arm 22 at an angle 90 to said long arm. The long arms of said levers lie in contact with a tapered portion 23 formed on the clutch ring 18 while the short arm of said levers extend through slots 24 formed in the hollow spindle 14. The 95 collar 19 is locked in position on said spindle by a lock nut 25 threaded onto the end of the spindle.

Arranged slidably in the hollow spindle 14, which may be termed an "outer spindle", 100 is a second hollow or inner spindle 26 which is rotatable with the outer spindle and has the core 27 of the work gripping or holding chuck secured thereto so that it moves lengthwise with said inner spindle. Said 105 core is slotted lengthwise from a point near its inner end to its outer end and the outer end is slightly enlarged and made conical to fit an inwardly flaring opening in the outer end of the chuck shell or casing, which 110

will be clearly understood, since such construction is common and is only one form of many commonly used chucks.

The outer end of the inner spindle 26 is engaged by the short inwardly extending arms 22 of the clutch levers 20, and when said levers are swung in one direction cause said inner spindle to be moved inwardly; whereas when said levers are swung in an opposite direction, the inner spindle is free to move outwardly or rearwardly.

The swinging of the clutch levers is effected by the movement of the clutch ring 18 which is actuated by a forked clutch arm 28, the forked end of which enters the annular groove 29 in said clutch ring and straddles the latter. This arm is splined on a carrier or supporting rod 30 fastened into the head stock in any suitable manner. Arranged transversely in the head stock is a rock-shaft 31 which has an arm 32 secured thereto, and connecting said arm with the clutch arm 28 is a link 33. The outer end of said rock-shaft is provided with a hand lever 34 for operating said shaft.

The parts thus far described are well known parts of a metal working machine and do not form any part of my invention, and reference is had to said parts only for the purpose of illustrating the manner of holding the work to be acted upon; and it is to be understood that any other machine capable of properly supporting the valve or other work-piece and allowing the work-piece to be properly positioned with reference to the cutting or trimming tools, to be hereinafter described, may be substituted therefor.

Slidably mounted at the opposite end of the bed or shears is a turret-slide 35 which may be moved lengthwise on the bed or shears by means of any common mechanism, such as now provided for this purpose in screw machines and other metal working machines of a similar nature. Any suitable means may also be provided to lock or retain said slide in any desired position and to stop the movement of the slide at the exact points desired. Mounted on said turret slide for rotatable adjustment, as is common, is a turret 36 which may be locked or retained in any adjusted position and which may be rotated during the sliding movement of the turret slide or independent of such sliding movement; such arrangements being in common use.

The turret has the usual peripheral sockets or openings 37, and in one of these a ram or work-positioning device 38 is fastened, said device comprising a shank 39 entered into one of the sockets 37, and a head 40 having a concaved contact face 41, the shank 39 being adjustable within the turret and locked in any adjusted position by one of the securing screws 42 with which the tur-

ret is provided. In the particular machine shown, the turret is provided with six sockets or openings arranged equi-distantly around the periphery thereof, and in a socket or opening adjoining that in which the ram or work-positioning device 38 is fastened, I secure a roughing-tool holder 43, the tool holder being therefore arranged at an angle of 60 degrees to the ram or work-positioning device.

The turret, turret-slide and parts carried thereby form no part of my invention and the slide and turret shown is of that type in which the turret is caused to rotate through a one-sixth of a revolution alternately in opposite directions each time the slide is moved back and forth, consequently with the parts in the position shown in Figs. 1 and 2, when moving the turret slide toward the head stock, the ram or work-positioning device has its axis coincident with that of the work-holding chuck and is moved toward said chuck. Upon reverse movement of the turret slide the turret is moved through a one-sixth of a revolution in the direction of the arrow 44, Fig. 2, which brings the roughing tool holder in line with the chuck so that when the turret slide is again moved forwardly or toward the chuck the roughing tool will be brought into operation against the valve or other work-piece. Upon again reversing the movement of the turret-slide the turret is reversed or caused to rotate through a one-sixth of a revolution in the direction of the arrow 45, Fig. 2, so as to again bring the ram or work-positioning device in line with the chuck. The manner of accomplishing this is not disclosed in the drawings due to the fact that it is embodied in a type of screw machine in common use. If desired, the turret may be rotated independent of the turret slide, as provided for in some types of metal-working machines.

Secured to the bed or shears 10 of the machine in any practicable manner is a table or fixed saddle 46 which has a pair of spaced lugs 47 extending from one side thereof, in which a shaft 48 is rotatably mounted having a gear wheel 49 secured thereto. Fastened to the bed or shears of the machine directly beneath the pair of lugs 47 is a second pair of lugs 50 in which is journaled for rotary movement a shaft 51 having a pinion 52 keyed or otherwise secured thereon, said pinion being in mesh with the gear wheel 49. To one end of shaft 51 a hand lever 53 is secured to rock the shaft 51 and cause rotation of the pinion 52, whereby reverse movement is imparted to the gear wheel 49.

At the opposite side of the table or saddle 46 a bracket 54 is secured, said bracket having a double acting lever 55 pivotally secured thereto, the lever having its pivotal point between its ends to provide oppositely

disposed arms adapted to move in opposite directions, the end of one arm having a link 56 pivotally connected thereto, which link has pivotal connection with a transversely 5 movable tool-slide 57 guided for movement on the table or saddle 46. Said table or saddle has a raised guide portion 58 with undercut side edges, which guide portion enters a correspondingly formed guide-way 10 59 formed in the underside of the tool slide 57. The table or saddle 46 is provided on its underside with a gear rack 60 with which the gear wheel 59 meshes. A second tool-slide 61 is mounted for transverse movement 15 on the tool slide 57 at one side of the longitudinal center of the machine, and said tool slide 61 has an adjustable link 62 connecting it with the double acting lever 55. The tool slide 57 is provided with a raised guiding 20 portion 63 having undercut side edges, while the tool-slide 61 has a correspondingly shaped guide groove 64 formed in its underside adapted to receive said guide portion.

Detachably secured to the tool-slide 61 is 25 a tool carrier 65, said carrier being fastened in position by a bolt 66 entered in a T-shaped slot 67 formed in said tool-slide, said slot being arranged lengthwise so that an adjustment of the tool carrier may be had in the 30 direction of the axis of the tool-holding chuck. The tool-slide 57 is also provided with a T-shaped passage 68 arranged lengthwise, and by means of a bolt 69 adjustable in said passage, a tool carrier 70 is secured 35 to said tool-slide. The tool carrier 70 is therefore also adjustable in the direction of the axis of the tool-holding chuck.

Secured to the tool carrier in any suitable 40 manner are the cutting tools 71, 72, respectively, these tools being adapted to cut or trim the different surfaces of the head of the valve or other work-piece simultaneously and preferably after the cutting or trimming action against the same by the roughing tool 73 secured to the holder 43. The 45 tool 71 is a grooved cutting or trimming tool, as shown in Fig. 5, and is adapted to cut or trim the seating face 74 of the head of the valve, the edge 75 thereof and a portion 50 of the upper or outer surface 76, as clearly shown in said figure, while the tool 72 is adapted to trim or shape the collar or hub portion 77 of the valve head. In order 55 that these tools may be easily retained in proper working condition and that they may last for a considerable length of time they are constructed of suitable cutting steel turned to a true circle with the marginal portion cut away, as at 78, Fig. 3, thus providing 60 an abrupt or radial cutting edge 79 which may be retained in sharpened condition and recede along the circular marginal portion until it is worn back to the cut away portion 78. Each of the tools 71, 72, has a 65 peripheral outline conforming to that which

the finished valve is to have at the points engaged by said tools.

By making the tools 71, 72, circular and providing the cutting edge shown, it is possible to retain said edge in proper position, as 70 it wears away by simply rotating the tool on the bolts 80 by means of which they are secured to the tool carrier.

The roughing tool is provided to roughly cut or trim the edge 75 of the valve head 75 and the upper or outer convex surface 76 thereof, and for this purpose it has a cutting edge 84 curved to the convexity which the upper or outer face of the valve is to have and with a cutting edge 85 arranged in 80 a horizontal plane to engage the edge of the valve head.

The operation of the device is as follows,—

With the parts in normal position, which 85 is that shown in Fig. 2, the valve is placed in position for cutting action by the operator by thrusting the stem thereof into the tool-holding chuck, and by means of the lever 34 the stem of the valve is slightly 90 engaged by the jaws of the chuck. The operator then moves the turret-slide forwardly so as to cause the ram or work-positioning device to engage the upper or outer convex surface of the valve and force 95 the valve-stem inwardly into the hollow spindle while a slight grasp is retained on the valve stem, thus assuring the proper positioning of the valve when the turret-slide reaches the end of its inward movement. At this moment the operator manipulates the lever 34 so as to cause the chuck to firmly grip the stem of the valve, and during this action the turret-slide may be returned or moved rearwardly by the 100 usual mechanism provided for this purpose. During this return or rearward movement the turret will be rotated through a one-sixth of a revolution to bring the roughing tool-holder 43 in line with the 110 valve, and since the turret-slide is operated with the right hand, the left hand is free to actuate the tool-slides 57 and 61. After the roughing tool-holder is brought in line with the valve the turret-slide is again 115 moved forwardly to cause the roughing tool to act against the outer or upper face of the valve-head, after which the operator depresses the lever 53 and causes the tool-slide 57 to move on the table or saddle 46 and 120 through the medium of the links 56, 62 and double acting lever 55 compel the tool-slide 61 to slide on tool-slide 57, the movements of said tool-slides being directly opposite so that the cutting tools 71, 72 are 125 simultaneously moved toward the axis of the valve. It is of course understood that these parts are properly adjusted so that the cutting edges of the tools 71, 72 will cut to trim the valves to exact size. With 130

a view of limiting the movement of the tool-slide 57, said slide has an outstanding lug 81 through which a stop screw 82 is passed that is adapted to engage an upstanding lug 83 formed on the table or saddle 46. When the several tools are moved out of engagement with the valve, the operator loosens the chuck from the valve stem and removes the valve so that another may be 10 positioned for action thereon.

Having thus described my invention, what I claim is,—

In a machine of the character described, the combination with a support and a rotatable work-holding element adapted to 15

hold a work-piece, of a tool slide movable at right angles to the axis of the work-piece, means for actuating said tool slide, a second tool slide movable on said first-mentioned tool slide at right angles to the 20 axis of the work-piece, a double-acting lever pivotally secured to said support, a link connecting one end of said lever with one end of said first-mentioned tool slide, a link connecting the opposite end of said lever with the corresponding end of said second tool slide, and a pair of cutting tools secured to said tool slides. 25

In testimony whereof I affix my signature.

AUGUSTUS E. SCHLIEDER.
